UNITED STATES PATENT OFFICE.

WILLIAM BAKER CLARKE, OF FRENCH LICK, INDIANA.

BURGLAR-ALARM.

SPECIFICATION forming part of Letters Patent No. 350,118, dated October 5, 1886.

Application filed March 11, 1886. Serial No. 194,813. (No model.)

To all whom it may concern:

Be it known that I, WILLIAM BAKER CLARKE, a citizen of the United States, residing at French Lick, in the county of Orange and State of Indiana, have invented certain new and useful Improvements in Burglar Alarms; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The special object of the invention is to set a trap for burglars, which will instantly ring a bell or fire off a gun, pistol, or other fire-arm as soon as they attempt to pass over it.

20 Figure 1 of the drawings is a perspective view showing my burglar-alarm set for automatic operation, and Fig. 2 is a side elevation.

In the drawings, A represents the base-plate upon which all the parts are arranged.

25 B is the fall, made of wire, pivoted in the eyebolts C C, and provided with the coil-spring, which has a constant tendency to throw it flat on the base-plate.

D is a lever fulcrumed between the top bifurcations e e of the screw-post E.

30 F is an end-bent bar, which may be made to catch at bottom on a right-angled staple, G, while at the top it holds one end of the lever D, so that the other end may maintain the fall in an erect position against the tension of spring H. The end-bent bar F is provided with an eye, f', on its back and preferably near its middle, so that it may be connected by the wires I with the fixed pins J, which are curved over at the top.

35 K represents fire-arms, which are trunnioned in supports L, so that the end carrying the load and the cap, or other means of exploding the powder, may be in the line of travel of the

hammer. The latter is on one end of a lever-handle, N, which is fulcrumed in studs n n. A cartridge and needle may be used, as shown in Fig. 2 of the drawings, and is preferable. The plate is arranged so that the end A' will be where the burglar will probably or necessarily step when he enters the house. As soon as he touches one of the wires I, the fall will be thrown with force on the helves or handles N of the hammers, when an explosion will take place, warning the household that burglars are on the premises.

If desired, the guns may be loaded with ball and arranged with respect to the end A' of the plate so as to shoot the robbers. Where used in barns, chicken-houses, or other out-buildings, this may be done without the objection, as in the house, that it is calculated to injure and deface the walls.

What I desire to protect by Letters Patent is—

1. In burglar-alarms, the combination of the base-plate A, the fall B, pivoted at C, the post E, having bifurcations e e, the bar F, bent at f f, the right-angled staples G, and the spring H, whereby the trap may be set, as described.

2. In a burglar-alarm, the combination, with the bar F, having the eye f' on its back, and connected with mechanism, substantially as described, of the wires I and fixed pins J, curved at the top, whereby the trap may be sprung, as described.

3. The combination, with a trap, substantially as described, of the fire-arms K, trunnioned in supports L, and the lever N, pivoted so at n, whereby a needle may be made to pierce a cartridge, as specified.

In testimony whereof I affix my signature in presence of two witnesses.

WILLIAM BAKER CLARKE.
